(57) **CLAIM**

The ornamental design for a comb, as shown and described.

DESCRIPTION

- 3.1 is a first perspective view thereof;
- 3.2 is a second perspective view thereof;
- 3.3 is a third perspective view thereof;
- 3.4 is a front view of the comb;
- 3.5 is a back view thereof;
- 3.6 is a left view thereof;
- 3.7 is a right view thereof;
- 3.8 is a top view thereof;
- 3.9 is a bottom view thereof;
